IGNITION APPARATUS

Charles Hall Davis, Jr., Anderson, Ind., assignor, by mesne assignments, to General Motors Corporation, Detroit, Mich., a corporation of Delaware

Application June 26, 1931, Serial No. 546,981

3 Claims. (Cl. 123—148)

This invention relates to ignition apparatus for internal combustion engines, and one of the objects is to provide ignition apparatus requiring less frequent renewal of spark plugs. A further object of the present invention is to provide certain improvements in ignition apparatus for relative high speed internal combustion engines. These objects are accomplished in the disclosed forms of the invention by the use of a plurality of ignition coils which are alternately charged and discharged through the operation of timed circuit breakers operated by a cam driven at one-half engine speed for a two cycle engine or one-fourth engine speed for a four cycle engine so that a series of sparking impulses are produced by alternately discharging the ignition coils. These impulses are distributed to the various spark plugs of the engine through a plurality of distributing circuits which are alternately operative to effect distribution. In the disclosed form of the invention the engine cylinders are provided each with two spark plugs so that the engine may be said to have two series of spark plugs. The distributing of the sparking impulses is such that, during one cycle of engine operation, one series of spark plugs first operates in continuity to fire the engine and during the following cycle of the engine the other series operates. In other words the spark plugs are used in two alternately operating series to fire the engine.

Further objects and advantages of the present invention will be apparent from the following description, reference being had to the accompanying drawing wherein a preferred embodiment of one form of the present invention is clearly shown.

In the drawing:

The figure of the drawing is a wiring diagram showing a form of the present invention.

Referring to the drawing, various engine cylinders 20 designated by I to VI respectively are arranged in firing order in the drawing but not necessarily in the order of mechanical connection with the engine crank case. Each cylinder is provided with two spark plugs, for example, #I is provided with spark plugs 1a and 1b. The various spark plugs are connected with distributor inserts or terminal posts 21. For example, spark plug 1a is connected with post 21#1a, and spark plug 1b is connected with terminal post 21#1b, these posts being diametrically opposite. The other spark plugs are connected in a similar manner. The various distributor posts 21 are arranged in a circular row concentric with a shaft 22 driven at one-half engine speed for a two cycle engine or one-fourth engine speed for a four cycle

engine and carrying two insulated distributing arms 23 and 24 which are at all times in contact with stationary distributor terminals 25 and 26 respectively, the latter being in the form of a ring. The members 25 and 26 alternately receive 5 sparking impulses from ignition coils 30 and 40 having secondaries 31 and 41 respectively connected with members 25 and 26 and having primaries 32 and 42 connected respectively with terminals 33 and 43. The terminals 33 and 43 are connected respectively by leaf spring conductors 34 and 44 with circuit breaker levers 35 and 45 respectively pivoted at 35a and 45a and carrying contacts 36 and 46 engageable respectively with grounded contacts 37 and 47. The pair of contacts 36, 37 is shunted by a condenser 38, and the pair of contacts 46, 47 is shunted by a condenser 48. The levers 35 and 45 carry respectively rubbing blocks 39 and 49 which are engaged by a cam 50 carried by the engine driven shaft 22. The primary coils 32 and 42 are connected by a switch 51 with a battery 52 grounded at 53.

The cam 50 rotates at one-half engine speed for a two cycle engine or at one-fourth engine speed for a four cycle engine to effect the alternate closing and opening of the pairs of timer contacts to effect the alternate charging and discharging of the coils 30 and 40. During each revolution of the shaft of a two cycle engine or each two revolutions of a four cycle engine the cam 50 makes a half turn and each coil will be discharged three times making a total of six sparking impulses. During one revolution of the shaft of a two cycle engine or each two revolutions of a four cycle engine, the series of engine plugs 1a, 2a, 3a, 4a, 5a and 6a will provide the gaps for the jump of the sparking impulses delivered thereto. It will be noted that the cam 50 which rotates clockwise is in such position that the contacts 36 and 37 have just separated. Therefore a sparking impulse will have been generated in the coil 30 and delivered from the secondary thereof to the central contact 25, thence through the distributing segment 23 to post 21#1a and then to spark plug 1a of cylinder 20#I. During 10 the following increments each of one-twelfth revolution of the distributor segments 23, 24 in a clockwise direction, the coil 40 will be discharged and the sparking impulse therefrom will be conducted through contact ring 26 and segment 24 to distributor post 2a and then to spark plug 2a of engine cylinder 20#II. Segment 23 distributes the next sparking impulse from the coil 30 to post 21#3a, then segment 24 distributes a sparking impulse from the coil 40 15 20 25 30 35 40 45 50 55

to post 21#4a, then segment 23 distributes a 5
sparking impulse from coil 30 to post 31#5a and
then segment 24 distributes a sparking impulse
from coil 40 to post 21#6a. Thus it is apparent
that the series of plugs, 1a, 2a, 3a, 4a, 5a, and 6a
receive sparking impulses from alternately dis- 10
charged ignition coils 30 and 40 during one
revolution of the engine shaft for a two cycle
engine or during two revolutions of the shaft of
a four cycle engine. During the following revolution
of the shaft of a two cycle engine or during
the following two revolutions of the shaft of a 15
four cycle engine, the series of spark plugs 1b,
2b, 3b, 4b, 5b, and 6b receive the next six spark-
ing impulses produced by the alternately dis-
charged coils 30 and 40. It will be apparent that
during this next rotation of the engine shaft,
segment 23 will conduct a sparking impulse
from coil 30 to post 21#1b, then segment 24 will
conduct a sparking impulse from coil 40 to post
21#2b. Then segment 23 will conduct a spark- 20
ing impulse from coil 30 to post 21#3b, then seg-
ment 24 will conduct a sparking impulse from coil
40 to post 21#4b. Next, segment 23 will conduct
a sparking impulse from coil 30 to post 21#5b
and then segment 24 will conduct a sparking im- 25
pulse from coil 40 to post 21#6b. This completes
the description of one cycle of operation of the
ignition apparatus which takes place in two
cycles of operation of either a two-cycle engine
or a four cycle engine. 30

By providing coils alternately discharged
through the agency of alternately operated cir- 35
cuit breakers operated each by a cam rotating
at one-half engine speed for a two cycle engine
or at one-fourth engine speed for a four cycle
engine, it is apparent that satisfactory ignition
can be provided for either a two cycle or a four 40
cycle internal combustion engine operated at
relative high speed.

A further advantage is that the spark plugs
will last longer than in conventional forms of
ignition apparatus since two sets of alternate- 45
ly operated spark plugs are provided.

While the form of embodiment of the present
invention as herein disclosed, constitutes a pre-

ferred form, it is to be understood that other
forms might be adopted, all coming within the
scope of the claims which follow.

What is claimed is as follows:

1. Ignition apparatus for an internal combus- 5
tion engine comprising, in combination, means
for generating a series of sparking impulses,
sparking devices with the engine cylinders, each
cylinder having a plurality of insulated sparking
device terminals thus providing the cylinders, 10
collectively, with a plurality of series of insulated
sparking device terminals, and means for dis-
tributing sparking impulses to one series of spark-
ing device terminals during one cycle of engine
operation and to another series during a follow- 15

ing cycle. 2. Ignition apparatus for an internal combustion engine comprising, in combination, means for generating a series of sparking impulses, sparking devices with the engine cylinders, each cylinder having a plurality of spark plugs each of 20
which has one insulated terminal thus providing
the cylinders, collectively, with a plurality of
series of insulated spark plug terminals, and
means for distributing sparking impulses to one 25
series of spark plug terminals during one cycle
of engine operation and to another series during
a following cycle.

3. Ignition apparatus for an internal combustion engine having N cylinders comprising, in 30
combination, sparking devices for the cylinders
each cylinder having two insulated sparking device terminals, means for generating sparking impulses and comprising two ignition coils, two
circuit interrupters respectively, for controlling 35
the coils, a cam having N lobes for operating the
interrupters alternately, said cam being driven
at one-half engine speed for a two-cycle engine
or at one-fourth engine speed for a four cycle
engine, and means for distributing the sparking 40
impulses and comprising two distributing seg-
ments rotating at interrupter cam speed and a
head having a circular row of 2N posts connected
respectively with the insulated sparking device
terminals. 45
